HANDLE

Perry W. Jester, Portland, Oreg.

Application July 28, 1943, Serial No. 496,436

1 Claim. (CL. 16—116)

This invention relates generally to the culinary art, and particularly to handles for utensils.

The main object of this invention is to provide a highly efficient form of handle adapted to resist the flow of heat to the hand of the user.

The second object is to provide a handle construction in which is employed a relatively weak material and which is a poor conductor of heat, in a manner that the resulting handle is exceedingly rigid and incapable of turning in its socket, and which will be practically scorch proof, and which cannot become too warm to handle comfortably.

I accomplish these and other objects in the manner set forth in the following specification, as illustrated in the accompanying drawing, in which:

Fig. 1 is a fragmentary side elevation of a handle showing a portion of the skillet.

Fig. 2 is a longitudinal section through a representative form of my improved handle.

Fig. 3 is an end elevation of Fig. 2, taken along the line 3—3.

Fig. 4 is a section taken along the lines 4—4 in Fig. 2.

Fig. 5 is a section taken along the line 5—5 in Fig. 2.

Fig. 6 is a fragmentary development of the perforated core.

Similar numerals refer to similar parts throughout the several views.

Referring in detail to the drawing, there is shown a skillet 10 having the usual socket 11 into whose base 12 is threaded a rod 13 provided with a ring 14 useful for turning the rod 13 or hanging the skillet when not in use.

Handles for skillets are commonly made of wood, but these char rapidly and deteriorate within the socket 11. The socket 11 is either made non-round as in the present illustrations, or provided with a key or lug to prevent the rotation of the handle therein.

In the present illustration, I prefer to provide a washer 15 which is octagonal in shape to correspond with the octagonal shape of the socket 11.

Extending slidably through the washer 15 is 5 the perforated tube 16 which is prevented from turning within the washer 15 either by making it non-round, or by keying. The tube 16 extends to the end washer 17 which contacts the ring 14. An enlarged washer 18 is preferably placed 10 around the end of the socket 11 to protect the end of the handle.

The handle 19 itself consists of the fibers of sugar cane or other heat resisting material which is preferably molded to shape in a manner that 15 the material will pass through the openings 20 in the tubular core 16, and support the relatively weak material in the handle 19 upon the reinforcing core 16.

While I have thus illustrated and described my 20 device, it must be understood that I do not intend to limit myself to the precise form shown herein, but I do intend to cover all such forms and modifications thereof as fall fairly within the appended claim.

25 I claim:

A handle consisting of a perforated polygonal tubular core, a hand engaging member of sugar cane fibre surrounding said core and extending through said perforations into the interior of said 30 core and having a central opening therethrough, a polygonal washer having a polygonal opening non-rotatably and slidably receiving one end of said core adapted to slidably fit into a socket mounted on a skillet, said socket means having a polygonal opening cooperating with the washer for preventing the relative rotation of said washer and socket, an end washer at the opposite end of 35 said handle and a handle bolt extending through said end washer and through said central opening having the threaded end of said bolt projecting beyond the socket end of said core.

PERRY W. JESTER.
